UNITED STATES PATENT OFFICE.

HERMAN SKERRY HALL, OF MALDEN, MASSACHUSETTS, ASSIGNOR TO THE VAPO COMPANY, OF BOSTON, MASSACHUSETTS, A CORPORATION OF MASSACHUSETTS.

MUFFLER.

1,070,956.

Specification of Letters Patent. Patented Aug. 19, 1913.

Application filed January 25, 1912. Serial No. 673,280.

To all whom it may concern:

Be it known that I, HERMAN S. HALL, a citizen of the United States, and a resident of Malden, in the county of Middlesex and 5 State of Massachusetts, have invented a new and Improved Muffler, of which the following is a full, clear, and exact description.

My invention relates to a muffler for internal combustion engines, and an object of 10 my invention is to provide an improved form of muffler in which it is possible to adjust the inlet relative to the outlet and which may be readily cleaned.

A further object of my invention is to 15 provide a muffler in which the cooling water is readily spread over a large area and swept out of the muffler at each explosion.

A further object of my invention is to 20 provide a muffler of such interior shape that the exhaust gas will obtain a rotary movement and will pass from the muffler tangentially.

A further object of my invention is to 25 provide a water drain which becomes effective when the muffler is in such tilted position that water cannot be ejected through the outlet.

Reference is to be had to the accompanying drawings, forming a part of this specification, in which similar characters of reference indicate corresponding parts in both 30 the figures, and in which—

Figure 1 is a plan view looking down upon a preferred embodiment of my invention, a portion of the head being broken away to show the upper baffle plate, and Fig. 2 is a transverse sectional view taken 35 on the line 2—2 of Fig. 1.

Described more in detail, my muffler is, 40 roughly, in the shape of a sphere, and consists of two hollow semi-spherical halves, an upper half 3, and a lower half 4, the meeting edges of which are formed into projecting flanges 5, suitably fastened together by 45 means of screws 6, with a suitable packing 7 interposed between the flanges 5. One side of the upper half 3 has extending therethrough, a suitable inlet 8, and extending from the bottom of the bottom 4 is a suitable outlet 9. In Fig. 2, the inlet 8 and the 50 outlet 9 are in the same plane, but due to the fact that the muffler is in two parts, the line of the inlet may be varied from the line of the outlet, by passing the screws 6 55 through suitably drilled holes in the abut-

ting flanges 5 of the two halves. It will be noted that the outlet 9 is substantially at the bottom 10 of the muffler, and, as shown in Fig. 2, this bottom wall gradually slopes down to the outlet, thereby facilitating the 60 draining of the water therefrom.

Threaded into the top of the upper half 3, is a water pipe 11, threaded to the lower end of which and within the muffler, is a distributing nipple 12, slightly projecting 65 into which nipple is the upper central portion of a perforated dome or baffle plate 13, the perforations 14 of which extending therethrough, are of greater cross-sectional area on the under side of the baffle than at 70 the top side, thereby forming apertures in the shape of frustums of cones. This dome 13 is centrally supported by means of a pipe 15, which pipe has its lower end in screw-threaded engagement at 16 with the center 75 of the bottom 10, and has just above the level of the bottom 10, a series of outlet apertures 17, adapted to afford a drain for surplus water that might accumulate on the bottom 10 when the muffler is tilted in such 80 position that the water is not forced through the outlet 9.

Usually the one baffle plate 13 is sufficient, but, if desired, an auxiliary baffle plate 18 may be supported on the pipe 15, below the 85 dome 13, which baffle may be of the flat perforated construction shown in Fig. 2, or, if desired, may be concave to assume a position indicated by the dotted lines in Fig. 2, or a plurality of these plates may be used. 90

By the above outlined construction, it will be seen that the water passing through the pipe 11 is distributed over the dome 13 in a relatively thin layer, so as to cool the exhaust and keep the muffler itself cool, the 95 shape of the water inlet protecting the water from the effects of the exhaust until it is spread over the dome 13. The introduction of the exhaust gas tangentially to the practically spherical shell, gives to the gas a rotary motion before it is swept through the outlet, this sweeping normally carrying with it, all of the water in the muffler. Further, when the vehicle together with the muffler, is ascending a hill, it is probable 100 that the explosive gas cannot sweep all of the water from the muffler, in which case, it is free to pass through the apertures 17 and out through this auxiliary outlet. 105

In place of the perforations 14, I may 110

make use of radially disposed elongated slots, which slots I consider the equivalent of said perforations.

Having thus described my invention, I claim as new and desire to secure by Letters Patent:

1. A substantially spherical muffler, comprising two semi-spherical parts, an inlet carried by one of said parts and an outlet carried by the other of said parts, means for securing the parts together so that the inlet and outlet may be arranged in the same or different planes, and means for introducing water to said muffler, said outlet being disposed to one side of and adjacent the bottom of the muffler, whereby water may be swept from said muffler by the explosive gases passing through said inlet.
2. A muffler having a gas inlet in the upper part thereof and an outlet in the lower part thereof, a water inlet in the top of said muffler, and a perforated dome-shaped baffle plate disposed below said water inlet, adapted to distribute water within the said muffler to be acted on by the gases passing in through said gas inlet in the muffler, and a second baffle plate below the dome-shaped baffle plate.
3. In a muffler, a casing having an inlet in its upper part and an outlet in its lower part, a water inlet at the top of the casing, and a plurality of baffle plates in the casing, one of the baffle plates being dome-shaped and perforated and arranged below the water inlet.
4. In a muffler, a casing having an inlet

in its upper part and an outlet in its lower part, a water inlet at the top of the casing, and a perforated baffle plate in the casing below the inlet and of a diameter approximately equal to the internal diameter of the said casing.

5. In a muffler, a casing having an inlet in its upper part and an outlet in its lower portion, a water distributing nipple projecting into the casing, and a dome-shaped baffle plate supported below the inlet of the casing and the distributing nipple and projecting slightly into the latter.

6. In a muffler, a casing having an inlet in its upper part and an outlet in its lower part, a water distributing nipple projecting into the casing, a dome-shaped baffle plate having conical apertures and of a diameter approximately equal to the internal diameter of the casing, and means for supporting the baffle plate projecting slightly into the distributing nipple.

7. A muffler having a water inlet in the central upper portion thereof, an arched dome positioned below said water inlet, and a pipe supporting said dome, said pipe having outlet apertures therein adapted to permit the draining of water from said muffler.

In testimony whereof I have signed my name to this specification in the presence of two subscribing witnesses.

HERMAN SKERRY HALL.
